[57] CLAIM

The ornamental design for a punch ball paddle, as shown and described.

DESCRIPTION

FIG. 1 is a perspective view taken from the top, front and side of a punch ball paddle, showing my new design;

FIG. 2 is a front elevational view thereof;

FIG. 3 is a rear elevational view thereof;

FIG. 4 is a side view thereof, the other side being a mirror image; and

FIG. 5 is a bottom plan view thereof.
